UNITED STATES PATENT OFFICE

2,094,883

KEY CONTROL FOR AUXILIARY PRINTING UNITS

Max Garbell, Chicago, Ill., assignor to Victor Adding Machine Company, Chicago, Ill., a corporation of Delaware

Application August 28, 1935, Serial No. 38,219

5 Claims. (Cl. 101—96)

This invention relates to a printing unit, and is more particularly directed to improvements in the operating mechanism therefor and key means for effecting the engagement of the operating mechanism with the printing unit which has been illustrated and described in my application for Letters Patent of the United States, Serial No. 720,397, filed April 13, 1934, and serves to render the unit operable or inoperable upon the operation of the machine to which it is attached.

For illustration, the printing unit and the key means for effecting the engagement of the operating mechanism therewith is shown as attached to an adding machine with the key means positioned in the keyboard of the machine and readily accessible for rendering the unit operable with the machine.

The main effect of the invention is to improve the type of unit control means illustrated and described in the above-mentioned application so that the operator of the machine may render the operating mechanism engageable with the unit upon the depression of the key therefor positioned in the keyboard.

Another object is the provision of novel key means for controlling the engagement of the operating mechanism with the unit so that it will be moved for an impact against a backing member upon the operation of the machine.

A further object is the provision of novel operating mechanism normally disengaged from the printing unit and having key means coacting therewith for connecting the mechanism with the unit prior to the operating movement of the machine to which it is attached.

A still further object is the provision of novel lock means, intermediate the key means and the operating mechanism, for retaining the key means when depressed, and being engageable by the operating mechanism to release the same upon the completion of operation of the machine.

With these and incidental objects in view, the invention includes certain novel features of construction and combination of parts, the essential elements of which are set forth in appended claims, and a preferred and modified form or embodiment of which is hereinafter described with reference to the drawings which accompany and form part of the specification.

In the drawings:

Figure 1 is a view in side elevation of the operating mechanism for the printing unit, showing my improved mechanism and key means for

effecting a connection between the operating mechanism and the unit.

Figure 2 is a rear view in elevation taken substantially on the line 2—2 of Figure 1, looking in the direction of the arrows.

Figure 3 is a side elevation similar to Figure 1, illustrating a changed position, with the key means depressed and the operating mechanism engaged with the unit.

Figure 4 is a top plan view of Figure 1.

Figure 5 is an enlarged longitudinal sectional view of the printing unit, illustrating its engagement with the operating mechanism.

Figure 6 is an enlarged detail perspective view of the lock means coacting with the key means.

Figure 7 is a modified form of the mechanism operable by the key means for engaging the operating mechanism with the unit; and

Figure 8 is a rear view in elevation, taken substantially on the line 8—8 of Figure 7.

The adding machine to which the invention is shown attached has a ribbon spool plate 10 and the usual digit keys 11 (one of which is shown), and the release bar 12 which is operated upon the completion of operation of the machine for releasing the digit keys to permit them to be restored to normal position. The release bar 12 is also operated manually by means of the total key 13 which engages an arm 14 thereon and which has a spring 15 fixed thereto retaining the release bar 12 readily operable.

The type bars 16 have the usual hammers 17 (Figure 4) which are common in their construction, being operable by means of the hammer-actuating shaft 18. A bifurcated arm 19 is fixed to the shaft 18 and serves to straddle a stud 20 carried on one leg of a rockable member 21 that is pivotally supported for rocking movements on a stud 22 fixed to the side wall 23 of the adding machine. The rockable member 21 has its other leg 24 provided with a bifurcated portion 25 that is adapted to be engaged by a stud 26 fixed to an arm 27 which is carried for rocking movements on a stud 28 fixed to the side wall 23 of the machine. This arm 27 is operatively connected to the driving mechanism of the adding machine (not shown), and intermittently engages the rockable member 21 for actuating the hammers as the machine is operated.

The printing unit 29 is mounted for reciprocating movements on the ribbon spool plate 10 adjacent one side of the type bars 16 of the adding machine and is adapted to be engaged by means of an arm 30 which is fixed to a shaft 31 pivotally carried in the side wall 23 of the ma-

chine. A depending arm 32 is fixed to one end of the shaft 31 and has its lower end portion provided with a bifurcated opening 33 for connecting the arm 32 with the rockable member 21.

To connect the depending arm 32 with the rockable member 21, novel means is provided, which consists of an engageable arm 34 pivotally carried on the rockable member 21 by means of a pin 35, and has a spring 36 connected thereto and to the rockable member 21 for normally maintaining a tension on the engageable arm 34 to retain a roller 37 carried on the free end thereof in sliding engagement with the arcuate edge 38 of a lever 39 carried for rocking movements on a stud 40 fixed to the side wall 23 of the machine. The lever 39 is normally retained with the arcuate edge 38 thereof depressing the engageable arm 34 by means of a spring 41 fixed thereto and to the side wall 23. The spring 41 yieldingly retains the free end of the lever 39 in abutting relation with an outwardly turned ear 42 of a depressible key 43 positioned in the keyboard of the machine and which is adapted to be manually depressed to actuate the lever. The depressing of the key 43 causes an upward rocking movement of that portion of the lever engaging the roller 37, and permits the engageable arm 34 to rock upward under the tension of the spring 36 fixed thereto until the roller 37 enters into the bifurcated opening 33 of the depending arm 32 and serves to connect the same with the rockable member 21, (Figure 3).

The key 43 is provided with an extending portion 44 that is adapted to engage a lock member 45 which retains the same and the lever 39, when depressed, so as to permit the roller 37 to remain in position to connect the depending arm 32 with the rockable member 21 until the operation of the machine has been completed. The lock member 45 is pivotally carried on the side wall 23 by means of a pin 46 and is constructed of two pieces, having a hook-like top member 47 and a lower member 48. The top member 47 is provided with an inwardly-turned portion 49 that is adapted to be engaged by an integral extending portion 50 on the lower member, and is yieldingly held by means of a spring 51, which also serves to retain the top member 47 readily engageable with the extending portion 44 on the key 43.

The lock member 45 is released upon the restoring movement of the arm 21 operated by the driving mechanism (not shown). The arm 21 has an extending integral lug 52 that is adapted to engage the lower member 48 of the lock member 45 which serves as a yieldable pawl in one direction of movement of the arm 21 and as an engageable member to release the lock member 45 from the depressed key 43 in the restoring movement of said arm.

It will be noted that the key 43 may be depressed with or independently of the total key 13 for making simultaneous impressions of the printing unit 29 and the type bars 16 of the machine, or for rendering the unit inoperable during the time the type bar impressions are being made.

In Figures 7 and 8, a modified form is illustrated in which the connection between the depending arm 32 and the rockable member 21 is made by means of a slidably mounted roller 53 carried for sliding movements in an elongated slot opening 54 in the arm of the rockable member 21, and guided for movements therein by means of a lever 55 having a bifurcated arcuate

opening 56 which straddles the roller 53 and which serves to elevate and lower the same in the slot opening 54 for effecting its engagement with the depending arm 32. The lever 55 is engaged for rocking movements on the stud 40 and is yieldingly urged in one direction by means of a spring 41 and engages the depressible key 43 in the same manner as that shown in Figures 1 and 3.

The lever 55 is provided with an inwardly-turned lug 57 that normally underlies the arm 14 of the releasing bar 12 and serves to engage to elevate the releasing bar as the key 43 is depressed. As the total key 13 is depressed, the arm 14 of the release bar 12 will be carried away from the lug 57 of the lever 55 without affecting the movement of the lever and the engagement of the roller 53 with the depending arm 32.

When the key 43 is depressed, the locking member 45 will retain the same in its depressed position and retain the lever 55 and the release bar 12 in locked position until the lock member 45 is tripped upon the restoring movement of the arm 21 actuated by the driving mechanism of the machine.

While the forms of mechanism herein shown and described are admirably adapted to fulfill the objects primarily stated, it is understood that it is not intended to confine the invention to the forms or embodiments herein disclosed, for it is susceptible of embodiment in various forms, all coming within the scope of the claims which follow.

I claim:—

1. A printing unit arranged for an impact against a backing member, an operating mechanism, a pair of members carried for rocking movements with and independently of each other, one of said members being operatively connected with the unit and said other member having a driving connection with the operating mechanism, manipulative means for effecting the engagement of the members for movement with the operating mechanism, said manipulative means comprising a rockable lever member, an engageable member for the pair of members and under the control of said lever member, key means rocking said lever member for controlling the movement of the engageable member to connect the pair of members with the operating mechanism to move the unit, and means coacting with the manipulative means retaining the same in its actuated position during the movement of the unit toward the backing member.

2. An operating mechanism for a printing unit, comprising a pair of members rockably carried in opposed relation to each other, an engageable member carried on one of said members and adapted to engage said other member, means normally retaining said engageable member disengaged, and manipulative means for effecting a movement of said last-mentioned means for causing the engagement of said engageable member with said other member.

3. An operating mechanism for a printing unit, comprising a pair of members pivotally carried in opposed relation for rocking movements with and independently of each other, one of said pair of members being operatively connected to the unit and said other member having a driving connection with an actuator, an engageable member carried on one of said members and adapted to engage the other member for movement therewith to move the unit, a lever normally retaining said engageable member disen-

gaged, and manipulative means for effecting a movement of the lever and said engageable member for connecting the pair of members.

4. The combination of claim 3 hereof in which there are means on the lever coacting with the engageable member for permitting of a movement thereof while said pair of members are connected thereby for movement with each other.

5. An operating mechanism of the character described, comprising a pair of members pivotally carried in opposed relation and adapted to be connected for a rocking movement with each

other, an engageable member for connecting the pair of members, and remote control means for effecting the engagement of said engageable member with said pair of members, said control means comprising key actuated means operatively connected with said engageable member for effecting its engagement with the pair of members and arranged and constructed to permit of a rocking movement of the pair of members while engaged or disengaged with each other.
